United States Patent Office

Des. 191,925
Patented Dec. 12, 1961

191,925

VENTILATOR

Donald E. Dailey, Center Township, Vanderburgh County, Ind., assignor to American Air Filter Company, Inc., Louisville, Ky., a corporation of Delaware

Filed May 2, 1960, Ser. No. 60,391

Term of patent 14 years

(Cl. D62—4)

FIGURE 1 is a perspective view of a ventilator showing my new design.

FIGURE 2 is an enlarged fragmentary view of the end and lower front panelling material.

FIGURE 3 is an enlarged cross sectional view of the panelling material taken on the line 3—3 of FIGURE 1.

The rear of the ventilator is substantially plain.

The end of the ventilator not shown is substantially the same in appearance as the end shown in FIGURE 1. The grille panelling material on the end of the ventilator is the same as that on the lower front thereof.

The grille panelling pattern is shown only in part on the end and lower area of the front. It is to be understood that the pattern covers the entire grille area.

The dominant features of my design reside in the full line portions.

I claim:

The ornamental design for a ventilator, as shown and described.
